UNITED STATES PATENT OFFICE.

WILLIAM MORTIMER MELMORE, OF LONDON, ENGLAND.

TIRE-INFLATER.

1,179,022.

Specification of Letters Patent. Patented Apr. 11, 1916.

Application filed June 15, 1915. Serial No. 34,319.

To all whom it may concern:

Be it known that I, WILLIAM MORTIMER MELMORE, a subject of the King of England, residing at London, England, have invented 5 a new and useful Tire-Inflater, of which the following is a specification.

This invention relates to tire inflators for application to one of the engine cylinders of a motor car, and my objects are to combine in a single device an air-inlet valve and a superposed non-return pressure valve with screw nipple for the inflator tube and means for locking one or both valves by stop-action.

15 I attain my objects by the device illustrated in the annexed drawings, in which:—

Figure 1 is a vertical section of combined superposed valves; Figs. 2 and 3, vertical sections of superposed valves with stop-20 action.

Referring to Fig. 1, the device for housing an air-inlet valve and a superposed non-return valve serves for temporary use on an engine cylinder in the place of a spark-plug, 25 or a compression tap, and consists of a shell 1 fitted with a spring-loaded valve 2 which covers a series of ports 3 in communication with the atmosphere. In an upper extension 4 of the shell 1 is lodged a ball-valve 5 which is held by a spring 6 retained in a delivery nozzle 7. When secured on the motor cylinder *a*, the valve 2 opens during the induction stroke of the engine piston 8 and allows air to pass through the ports 3 and the annular space 9 of the shell 1 into the engine cylinder 10, the air being compressed and forced out at the compression stroke through the central opening 11 of the valve 2 against the lifting ball 5 and 35 through the nozzle 7 to the flexible tubing 12 for delivery into a tire. The nozzle 7 can be screwed down to lock the ball 5.

Referring to Figs. 2 and 3, a device similar to that shown in Fig. 1 is provided with

a stop valve and serves for permanent application in lieu of the ordinary exhaust valve-cap. In these figures the upper parts of the device are constructed and arranged in the same manner and identified by the same characters as those in Fig. 1. The stop 45 valve 13 is rigidly secured to the lower extension 14 of the shell 1 and, with the superposed inlet and outlet valves, is moved up and down in the valve cap 15 which has a lower aperture 16. When the stop valve 13 50 is moved down tight over the aperture 16, position shown in Fig. 2, the motor cylinder will receive its usual supply of explosive mixture and act as a power cylinder. When, however, the valve 13 is moved up, position 55 shown in Fig. 3, the mixture will be drawn into the other motor cylinders, and according to a known method only air will enter the cylinder to which the device is connected so that such cylinder is immediately converted into an air-compressor. At the suction stroke pure air is drawn through the ports 3, open valve 2, annular space 9, apertures 16 and into the cylinder. At the compression stroke, the valve 2 closes and the 60 compressed air forces the loaded ball valve 5 open and passes through the nozzle 7 and any flexible tubing into a tire, as usual.

I claim:—

A valve comprising a chamber composed 75 of two members one of said members having a plurality of ports and an outwardly-directed tube, a valve in said tube, a disk to close said ports and means to hold said disk in place; the other of said members 80 having means for engagement with a cylinder.

Signed at London, England, this 3rd. day of June 1915.

WILLIAM MORTIMER MELMORE.
